UNITED STATES PATENT OFFICE.

MINOT C. BLEST, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

DOOR-OPERATING MECHANISM.

1,390,333.

Specification of Letters Patent. Patented Sept. 13, 1921.

Application filed May 10, 1921. Serial No. 468,300.

To all whom it may concern:

Be it known that I, MINOT C. BLEST, a citizen of the United States, residing in Bellevue, in the county of Allegheny and State of Pennsylvania, have invented certain new and useful Improvements in Door-Operating Mechanism, of which the following is a specification.

This invention relates to railway dump cars and particularly to the type of dump car in which the discharge door operating shafts are disposed longitudinally of the car and located between the center and side sills of the car (the center sills not being illustrated) upon the lower edge portion of the side sills and has for an object the provision of means for operating a discharge door operating shaft which terminates short of the ends of an adjacent side sill and is located between the center and side sill in a plane upon the lower edge of the side sill, thus obviating the necessity of extending the shaft beyond the ends of the side sill to accommodate the operating and locking mechanism.

Another object of the invention is to provide an operating lever or socket which extends below the side sill of a car where it is easily accessible to an operator, which lever or socket, when being operated to open or close the discharge doors, is movable to such a position that portions thereof extend beyond the outside lines of the side sill.

A further object of the invention is to provide an operating lever or socket with a reversible pawl mechanism, which pawl when in one of its preferred positions is held against accidental movement.

These and other objects will be apparent from the following description.

Referring now to the drawings in which like reference characters refer to like parts, Figure 1, is a side elevational view of a portion of a car embodying the invention; Figs. 2 and 3 are enlarged sectional views of the same taken on the lines 2-2 and 3-3 respectively of Fig. 1, and Fig. 4, is an enlarged sectional view taken on line 4-4 of Fig. 2. Figs. 5 and 6 are enlarged sectional views which correspond to Figs. 3 and 4 respectively showing a modification of the invention and Fig. 7 is a sectional view corresponding to Fig. 2 showing such modification. Fig. 8 is a sectional view

corresponding to Fig. 2, showing a further modification of the invention.

Referring now in detail to the drawings the reference character 1 indicates the underframe of the car, (a portion only of which is illustrated) which underframe comprises side sills 2 and transverse members 3 which members at their ends are connected with the side sills. The floor of the car is provided with a plurality of drop doors 4 each of which at one side is hinged to the underframe in any desired manner. The end portions 5 of the floor of the car are stationary and are secured to the underframe and between such portions the doors 4 are arranged. The side walls of the car may be of any suitable construction, but in the present embodiment of the invention have been shown as comprising longitudinal sheathing boards 7, coping angle 8, vertical metallic stakes 9 and diagonal metallic braces 10, such stakes and braces being secured at one end to the coping angle and at the opposite end being secured to the side sill.

Beneath the drop doors and inwardly from the side sills, door operating shafts 11 are provided which extend longitudinally of the car and terminate short of the ends of the side sills. Each of these shafts is loosely mounted, above the lower edge portion of the side sill, in slotted bearing members 12 which are secured to the transverse members 3 of the underframe. Between these transverse members the shaft is provided with rollers 13 having a chain winding portion 14, such rollers being adapted to engage shoe members 15 mounted on the doors 4. To operate the doors a flexible member may be provided which at one end may be secured to the chain winding drum 14 and at the opposite end to the shoe member 15. In this embodiment of the invention the shaft is rotatable and bodily movable. When the shaft is rotated in the direction as indicated by the arrow in Fig. 3, the rollers 13 which are serrated will engage serrated portions of the shoe members 15 and will cause the shaft to move bodily in a direction toward the side sill, and when rotated in the direction opposite to that indicated by the arrow in Fig. 3 will cause it to move bodily in a direction away from the side sill.

The operating shaft extends through and

beyond the transverse member 3 and bearing member 12 which are adjacent the end drop door, the portion of the shaft projecting beyond the bearing member 12 being preferably square. The round portion of the shaft is rotatably mounted in a bearing member 17 which is slidably mounted in the bearing member 12, such bearing member 17 having a vertically disposed portion 18 which extends inwardly beyond the shaft. This portion is provided with an outwardly extending lug 18a upon which a pawl 19 is rotatably mounted and adapted to be moved into and out of engagement with a ratchet wheel 20 mounted on the square portion of the shaft, and is further provided with a lug 21 upon which a dog 22 is rotatably mounted and adapted to be moved into and out of engagement with the pawl 19.

20 For the purpose of rotating the shaft a ratchet mechanism is provided which comprises a ratchet wheel 23 and a lever socket member 24. The ratchet wheel 23 is mounted on the square end portion of the shaft and is held in its proper position by members 25 which are secured to the shaft. These members are provided with bushing portions 26 upon which spaced portions 27 of the lever socket member are rotatably mounted and are further provided with collars 28 adapted to prevent movement of the lever in a direction longitudinally of the shaft. Below the shaft this lever is provided with a socket portion 29 adapted to receive a suitable operating lever. When the discharge doors are in their normal closed position the socket portion is disposed in a horizontal plane as shown in full lines in Figs. 1, 2 and 4 where it is easily accessible to the operator for inserting an operating lever and for operating the discharge door operating mechanism. When the doors are in their normal open positions the socket portion of the lever extends outwardly beyond the side sill and the opening for the reception of the lever is disposed upwardly. The ratchet wheel 23 is arranged between the spaced portions 27 of the lever socket and is adapted to be engaged by a pawl 30 which is arranged between and pivotally connected with the spaced portions 27. This pawl is provided with ratchet wheel engaging portions 31, one of which is adapted to engage the ratchet wheel to rotate the shaft in one direction and the other adapted to engage the ratchet wheel to rotate the shaft in the opposite direction. Between the portions 31 the pawl is provided with a projection 32 having sloping surfaces 33 and 34 which are adapted to be engaged by a member 35 loosely mounted in a socket 36 formed in the lever socket. Within the socket 36 a spring 37 is arranged, the upper end portion of which is adapted to engage the member 35 and hold such member in close contact with the projection 32

of the pawl at all times. When the discharge doors are being opened the member 35 engages the surface 33 of the projection 32 and when the doors are being closed such member engages the surface 34, the position 70 of the pawl being changed by the operator. It will here be noted that the member 35 and spring 37 will prevent the pawl from becoming accidentally disengaged from the ratchet wheel and at the same time will permit such pawl to be easily moved by the operator to its different operative positions. It will further be noted that as the operating shaft moves bodily the bearing member 17, pawl 19, ratchet wheel 20, dog 22 and 80 ratchet mechanism will move with the shaft.

In Figs. 5, 6 and 7 a modification of the invention has been illustrated in which the shaft rotates but does not move bodily.

In Fig. 8, a modification of the lever socket 85 has been illustrated which may be applied to a bodily movable and rotatable shaft or to a rotatable shaft. The socket portion of this lever when the doors are in their open positions being wholly outside the lines of the 90 side sill and being disposed substantially vertical.

Having thus described the invention what I claim as new and desire to secure by Letters Patent is:—

1. In a dump car, a sill, a discharge door operating shaft behind said sill and an operating lever mounted on said shaft having a socket portion depending below said sill, said socket portion being movable beyond the outside vertical lines of said sill. 100
2. In a dump car, a sill, a bodily movable discharge door operating shaft behind said sill, and an operating lever mounted on said shaft and being movable therewith, the end portion of said lever being movable to a position beyond the outside vertical lines of said sill. 105
3. In a dump car, a sill, a bodily movable and rotatable shaft behind said sill, and an operating lever mounted on said shaft and being movable therewith, said lever having a socket portion depending below said sill and movable to a position beyond the outside vertical lines of said sill. 110
4. In a dump car, a sill, a discharge door operating shaft behind said sill, a ratchet wheel mounted on said shaft, an operating lever rotatably mounted adjacent said ratchet wheel and depending below said sill, a reversible pawl pivotally mounted on said lever adapted to engage said ratchet wheel, a projection on said pawl and means engaging said projection for holding said pawl in engagement with said ratchet wheel in 125 one of its positions.
5. In a dump car, a sill, a discharge door operating shaft behind said sill, a ratchet wheel mounted on said shaft, an operating lever rotatably connected with said shaft and 130

depending below said sill, a reversible pawl
on said lever adapted to engage said ratchet
wheel, a projection on said pawl having a
plurality of sloping faces, a member loosely
5 mounted on said lever adapted to engage
said faces and means for holding said mem-
ber in engagement with said projection.

In testimony whereof I affix my signature
in the presence of two witnesses.
